UNITED STATES PATENT OFFICE.

WILLIAM L. VAN NOSTRAN, OF CINCINNATI, OHIO.

NECKTIE.

1,100,164.

Specification of Letters Patent. Patented June 16, 1914.

Application filed May 18, 1912. Serial No. 698,152.

To all whom it may concern:

Be it known that I, WILLIAM L. VAN NOSTRAN, a citizen of the United States, and a resident of the city of Cincinnati, in the 5 county of Hamilton and State of Ohio, have invented certain new and useful Improvements in Neckties, of which the following is a full, clear, and exact description, reference being had to the accompanying drawing, forming part of this specification.

My invention relates to neckties of what is known as the four-in-hand type, comprising in its ordinary form a scarf of any suitable material with a broad, usually flaring end, and a narrower, somewhat less flaring end, the two ends connected by a narrow neck band. In tying this style of necktie, the neck band is passed around the collar and the broader end is knotted in front 10 over or around the narrower end, thus taking up a portion of the broader end and permitting the knot to be drawn tight by sliding it on the narrower band and allowing the two flaring ends to hang loose and about 15 of even length. The ordinary four-in-hand tie has to be tied and untied each time it is used, and in order to maintain a substantially even length of ends, the knot must be made each time in substantially the same 20 place on the scarf, otherwise one end will project below. This constant tying in one place causes excessive wear at this portion of the tie, crumpling and crushing the material, and soiling it, besides consuming much 25 time and patience. As both ends of the scarf are loose, the entire scarf has to be manufactured of the same material throughout, thus adding largely to the cost of the necktie. In adjusting the knot to make it 30 fit properly underneath the collar, the band has to be pulled back and forth around the collar, and this frequently causes the neck band to tear where it passes over the collar button.

It is to obviate all of these disadvantages 35 that my invention is directed, and it consists of that certain novel construction to be hereinafter particularly pointed out and claimed, whereby the visible portion of the 40 scarf shall comprise only one flaring end, with the narrow neck band portion extended

to the opposite end and adapted to be concealed when the scarf is tied by the finished flaring or wide end of the scarf, so that when desired the concealed portion may be 55 manufactured of cheaper material of the narrow width of the neck band. Moreover, provision is made for an increased length of the narrow portion, and to take up this increased length by a loop of the narrow material at the end which can be adjusted to 60 any extent desired, to be concealed by the wider and visible portion of the scarf, whereby, by reason of the length of the narrow portion, the loop can be drawn out to 65 permit removal of the scarf by sliding the knot down on the narrow end to enlarge the loop, to allow it to pass over the head of the user without untying or disturbing the knot. In this way, when once tied, the scarf shall 70 not be subjected to tying and untying, to damage and soil the material, and to exhaust the patience of the user, and the life of the scarf may be very materially prolonged, and in case the knot should become 75 soiled, the tie can be retied in a clean portion, and the length properly adjusted by the loop. Two scarfs can thus be manufactured out of the same amount of the most expensive and fancy material heretofore required for a single scarf, and the expensive 80 material is not subjected to the wear and damage to which such material has heretofore been subjected.

In the drawing, Figure 1 is a perspective 85 view of my improved scarf as in use. Fig. 2 is a perspective view, showing the scarf untied, partly broken away. Fig. 3 is a perspective view of the narrow band portion of the tie, showing one device for attachment 90 to the body of the tie. Fig. 4 is a perspective view of the preferred form of the combined slide and clasp.

The body of the scarf is formed of any suitable material, one end, as 1, being flaring or broad, and this end being reduced 95 to a narrow portion 2 for passing around the neck, the reduction in width being usually made by tapering the sides between the broad and the narrow band. It is usual to 100 tie the scarf into the knot employed for the four-in-hand tie at this tapering portion.

Instead of broadening out the other end of the tie to correspond with the broad portion 1 and providing a scarf of proper length, so that when properly tied, the ends will hang loose the desired distance in front of the shirt, I maintain the narrow width of the neck band, and provide this narrow width for the opposite end of the scarf much longer than would be required for the ordinary four-in-hand tie, and loop the lower end of the narrow end 3 on itself, as shown at 4. The extreme end of the narrow portion is secured to a clasp 5, comprising a closed loop 6, preferably with a lateral extension 7 which is brought back and over the closed loop at 8. The extreme end of the end 3 is secured to the clasp 5, and the end passed back through the closed loop 6 so as to form the loop 4, and the end of the band can thus be taken up or made shorter by sliding the clasp on the band. This providing the loop for the outer end of the narrow end 3 forms an important part of my invention, inasmuch as without this looped portion the end of the band would extend so far below the broad end 1 as to be unsightly and objectionable, and thus prevent the use of the scarf.

The narrow end of the scarf may be of the same material as the broad wider end, and the scarf may be formed of a single piece; but in the usual embodiment of my invention, I prefer to form the narrow band of different and cheaper material. This band will preferably be made of tape or braid of the same general color and appearance as the body of the tie, and it will be attached to the body of the tie by sewing, as at 10, or a fastener 11 may be provided, and the inner end of the band attached by this fastener to the body of the tie. With this narrow band looped on itself, the scarf is tied in the usual way for a four-in-hand tie, the knot being formed at the tapered portion of the body 1 and being tied around the narrow band and adjusted in place. The narrow band being underneath the wide flaring end, may be held entirely concealed by the ordinary scarf pin, the lower end of the narrow band being looped up so as to prevent it projecting below the lower edge of the flaring portion.

While a scarf pin alone may be employed to fasten the narrow band out of sight, I prefer to use the clasp 5 and to pass the side of the tie underneath the portion 8, and inasmuch as this portion extends laterally from the loop 6, the narrow end of the tie will be brought directly behind the scarf and completely concealed. This portion 8 of the clasp may be finished ornamenteally, or engraved with an initial, and may readily serve as an ornamental addition to the tie, taking the place of the scarf pin, or tie holder. The main use of the clasp, how-

ever, is to serve as a slide for adjusting the length of the end of the narrow band.

My object in providing a much longer, narrower end for the scarf than usual and in forming this end of the width of the narrow neck band portion throughout, is to permit the taking off and putting on the scarf without untying the knot. The loop is shortened and the narrow band merely drawn through the knot until a sufficient loop is furnished around the neck to admit of passing over the head. In this way, any one may use the four-in-hand tie, even though they may not be sufficiently skilful to tie the desired knot, inasmuch as the knot once being tied, does not need to be untied. This, as already pointed out, very materially reduces the wear on the scarf, and prevents soiling.

Having thus described my invention, what I claim as new and desire to secure by Letters Patent, is:—

1. A necktie comprising a scarf with one broad end, a neck band, and a narrow end being of substantially uniform width throughout and of a length substantially the combined length of the broad end and the neck band, and means for holding the narrow end concealed when the scarf is tied, the narrow end being provided with an adjustable loop and means for taking up the loop to adjust the length of the narrow end to conform to the length of the broad end when tied, and to extend the loop to permit removal and replacement of the scarf without untying the knot.

2. A necktie comprising a scarf with one broad end, a neck band, and a narrow end the width of the neck band, the narrow end being of substantially uniform width throughout, and of a length substantially the combined length of the broad end and the neck band and provided with an adjustable loop and means for taking up the loop to adjust the length of the narrow end to conform to the length of the broad end when tied and to extend the loop to permit removal and replacement of the scarf without untying the knot.

3. A necktie comprising a scarf with one broad end, a neck band, and a narrow end the width of the neck band, the narrow end being of substantially uniform width throughout, and of a length substantially the combined length of the broad end and the neck band, a clasp secured at the extremity of the narrow end and slidably mounted on the narrow end portion to form an adjustable loop to adjust the length of the loop for the purpose described.

4. A necktie comprising a scarf with one broad end, a neck band, and a narrow end the width of the neck band, the narrow end being of substantially uniform width

throughout, and of a length substantially the combined length of the broad end and the neck band, a clasp secured at the extremity of the narrow end and slidably mounted on the narrow end portion to form an adjustable loop to adjust the length of the loop for the purpose specified, the clasp

provided with a lateral extension to engage over the broad end to conceal the narrow end from view.
